UNITED STATES PATENT OFFICE.

CHESTER MCNEIL, OF CHICAGO, ILLINOIS, ASSIGNOR TO UNION SPECIAL MACHINE COMPANY, OF CHICAGO, ILLINOIS, A CORPORATION OF ILLINOIS.

FEEDING MECHANISM FOR SEWING-MACHINES.

1,112,078.

Specification of Letters Patent. Patented Sept. 29, 1914.

Application filed June 3, 1904. Serial No. 211,004.

To all whom it may concern:

Be it known that I, CHESTER MCNEIL, a citizen of the United States, residing at Chicago, in the county of Cook, State of Illinois, have invented certain new and useful Improvements in Feeding Mechanisms for Sewing-Machines, of which the following is a description, reference being had to the accompanying drawing and to the letters and figures of reference marked thereon.

My invention relates to an improvement in feeding mechanism for sewing machines, and particularly to a feeding mechanism such as illustrated in the application filed by Russell G. Woodward, on the 9th day of November, 1901, Serial No. 81,770, patented October 24th, 1905, No. 802,789, in which an inclined feed dog is used, a portion of which engages the fabric ahead of the needles, and crowds said fabric up toward the same, so that when the stitches have been placed in said fabric, and it comes out from the machine, it will not be puckered. This inclined feed dog is pivoted to its support and adjustable to vary the inclination. It has been found in practice with said inclined feed dog that where it is squared off in front, and is tilted to such position that the forward end extends above the top of the throat plate, that the goods will catch against the edge and will not begin to feed properly.

The object of the present invention is to provide a construction of inclined feed dog wherein the front end of the feed dog will always be in proper co-operative relation to the fabric for all positions of adjustment of said feed dog.

The invention consists in the matters hereinafter described and referred to in the appended claims.

In the accompanying drawings, which illustrate the invention, Figure 1 is a perspective view of so much of a sewing machine as is necessary to an understanding of the invention; and Fig. 2 is a sectional view of the feed dog and adjusting device.

In these drawings, A represents the bed of the machine; B the needle bar; C the presser bar; D the presser foot; and E the cloth plate. The feed dog *c* is pivoted to the feed bar 1, by a pivot bolt 2, and a rod 3 carried by the feed bar has a ball joint connection 4, with said feed dog. By means of the thumb nut 5, the rod 3 may be rotated. Said rod 3 has a screw thread con-

nexion with its support, and when rotated moves longitudinally of the feed bar, thus tilting the feed dog. The feed dog is shown as inclined generally from front to rear, but at the front end of the feeding surface proper, it is tapered or rounded, as at *a*, in order that when the goods are placed in the machine, they will not encounter the straight front wall of the feed dog, but will be placed underneath the presser foot in proper position, and as the feed dog rises the fabric will be first engaged by the tapered off front portion, and have its free end forced up, and if it is provided with teeth will be fed slightly, and as fed along it will be taken up by the feeding surface proper.

It will be understood that I do not wish to be limited to the exact details shown herein.

Having thus described my invention, what I claim as new, and desire to secure by Letters Patent, is:

1. A sewing machine including in combination, a cloth plate, a needle and a feeding mechanism comprising a feed dog, adapted to engage the material in front of the needle, means for projecting said feed dog through the cloth plate to engage and feed the work, said feed dog having the forward end of its feeding surface inclined downwardly and forwardly relatively to the rearward portion of said surface and beneath the surface of the cloth plate, said inclined forward portion having feed teeth thereon, and means for adjusting the relative position of the feed dog and cloth plate.

2. A sewing machine including in combination, a cloth plate, a needle, and a feeding mechanism comprising a feed dog, adapted to engage the material in front of the needle, means for projecting said feed dog through the cloth plate to engage and feed the work, said feed dog having the main portion of its feeding surface inclined downwardly and rearwardly, and its front portion inclined downwardly and forwardly beneath the surface of the cloth plate, said inclined forward portion having feed teeth thereon.

3. A sewing machine including in combination, a cloth plate, a needle, and a feeding mechanism comprising a pivoted feed dog adapted to engage the material in front of the needle, means for tilting said dog, means for projecting the same through the throat plate to engage and feed the work, said feed

- dog having the forward end of its feeding surface inclined downwardly and forwardly relatively to the rearward portion of said surface and beneath the surface of the cloth plate, whereby the feeding of the fabric is not impeded by the end of the feed dog in its various tilted positions.
4. A sewing machine including in combination, a cloth plate, a needle, a feeding mechanism comprising a pivoted feed dog adapted to engage the material in front of the needle, means for tilting said dog, means for projecting the same through the throat plate to engage and feed the work, said feed dog having the main portion of its feeding surface inclined downwardly and rearwardly, and its front portion inclined downwardly and forwardly beneath the surface of the cloth plate, whereby the feeding of the fabric is not impeded by the end of the feed dog in its various tilted positions.

5. A sewing machine including in combination, a cloth plate, a needle, a feeding mechanism comprising a feed dog adapted to engage the material in front of the needle, means for projecting the feed dog through the cloth plate to engage and feed the work, said feed dog having the main portion of its feeding surface inclined downwardly and rearwardly, and its front portion inclined downwardly and forwardly beneath the surface of the cloth plate, said main portion and said front portion having teeth projecting outwardly at substantially the same angle to the surface of the feed dog.

In testimony whereof I affix my signature in presence of two witnesses.

CHESTER McNEIL.
